RETRIEVABLE COMBINATION BRIDGE
PLUG AND PACKER

Bowen Monroe Davis, Laird Hill, Tex.

Substitute for abandoned application Serial No.
271,528, May 3, 1939. This application November
7, 1940, Serial No. 364,703

5 Claims. (Cl. 166—12)

This invention relates to oil well packers. This application is a substitute for abandoned application Ser. No. 271,528, filed May 3, 1939.

An object of this invention is to provide an oil well packer having means to grip the oil well casing when the packer has been lowered a desired distance in the oil well, and means to release the packer when it is desired to remove the packer from the oil well.

A further object of this invention is to provide a strong, rugged, and compact oil well retrievable casing plug of the character described, which shall be relatively inexpensive to manufacture, positive in operation, yet practical and efficient to a high degree in use.

Other objects and advantages of the invention will be apparent from the following detailed description of the accompanying drawings, in which:

Fig. 1 is a side elevation of a retrievable oil well casing plug embodying one construction of the present invention, within an oil well casing, with parts in cross-section and parts broken away.

Fig. 2 is a cross-sectional view taken on line 2—2 of Fig. 1.

Fig. 3 is a cross-sectional view taken on line 3—3 of Fig. 1.

Fig. 4 is a side elevation illustrating another embodiment of the present invention, within an oil well casing, with parts in cross-section and parts broken away.

Fig. 5 is a cross-sectional view taken on line 5—5 of Fig. 4.

Fig. 6 is a cross-sectional view taken on line 6—6 of Fig. 4.

Referring now to Figs. 1, 2, and 3 of the drawings in detail, 1 designates an oil well casing, in which is suspended by a cable from the derrick in the usual manner, an oil well packer embodying the invention.

The packer comprises a cylindrical body 2, having adjacent its lower end an enlarged bore 3, and having in its lower end a plurality of slots or rectangular longitudinal openings 4, and at the extreme lower end of body 2, internal screw threads 5.

Screwed to the screw threaded portion 5 of the packer body 2 is a packer adapter 6 formed with an internal screw threaded portion in which a bull plug 7 is fastened. The adapter 6 has for a substantial portion of its length a cylindrical surface, and near its lower end a downwardly and outwardly inclined external surface 8.

The body 2 is formed adjacent the upper end 55

thereof, with an external shoulder 9, and with an upwardly and outwardly extending conical external surface 10. The packer body 2 is also formed with diametrically opposed openings 11 to receive the pins 49 of the setting tool later described.

Slidably mounted within the packer body 2 is a recovery nipple or sleeve 12, the upper portion having an external surface 13 arranged to slide on the inner surface of the upper portion of the packer body 2. The lower portion 14 of the sleeve 12 has an outer diameter such as to slide on the inner surface of the bore 3. The enlarged bore 3 of body 2 forms a shoulder 15 which acts as a stop for shoulder 15 of the recovery nipple 12 when nipple 12 is moved upwardly.

Relative movement between the body 2 and the sleeve 12 is prevented by a shear pin 17, said pin serving to retain the sleeve 12 in contact with the upper edge of the adapter 6. The sleeve 12 is formed adjacent the upper end thereof and on the inside thereof, with an annular groove 18, forming an annular hooked bead 19 for the purpose hereinafter explained.

Surrounding the packer adapter 6 is a rubber packer sleeve 20, its lower end shaped with an internal conical face 21 to fit face 8 of adapter 6, and its upper end shaped with an internal conical face 22 to fit an external conical shaped face 24 which is on the lower end of ring 23 which surrounds the lower end of body 2.

Ring 23 normally covers the lower end portion of body 2, and also the lower ends of the openings 4 in said body. Slidably mounted within each of the openings 4 for vertical sliding movement, is a setting block 25. The setting blocks 25 have inner part-cylindrical surfaces contacting the outer surface of portion 14 of the recovery sleeve 12. Each setting block 25 furthermore has an external downwardly and outwardly inclined surface provided with a longitudinal dove-tailed groove 29.

Slidably mounted within said groove 29 of the setting blocks 25, is a lower slip 30, having a male dovetail section 32, and provided with upwardly pointed teeth 31 adapted to grip the inner surface of the oil well casing 1, normally permitting the packer to be moved downwardly and serving to grip the oil well casing when the packer is moved upwardly.

Setting blocks 25 are held in place by their lower ends being positioned between the upper edge of ring 23 and the lower portion 14 of sleeve 12. The upper ends 27 of said blocks are covered

by a sleeve 33 having at its lower end an external circumferential shoulder 34. The lower end of sleeve 33 is chamfered on the inside to rest against a short tapered face 28 on the upper external face of blocks 25.

Sleeve 33 is provided with a section 35 of reduced external diameter which is telescoped into another sleeve 36. Sleeve 36 has at its upper end a circumferential shoulder 37 which is provided with a plurality of slots 38. Directly under shoulder 37 are diametrically opposed holes the function of which will be explained hereinafter. In the slots 38 are screwed or welded spring arms 40 which extend upwardly and terminate in the upper slips 41, said slips having external downwardly pointed teeth or wickers designed to grip casing 1, and said slips having an internal downwardly and inwardly inclined surface resting against surface 10 of body 2.

Encircling the sleeves 33 and 36 is a helical spring 42 which bears at its upper end against shoulder 37 and at its lower end against shoulder 34.

The packer is held with the upper slips in a retracted position by a setting tool which comprises an outside cylindrical section 43 whose upper part is shaped externally to slidably fit the upper internal end of the packer body 2 and whose lower end is reduced externally to slidably fit the inside of recovery sleeve 12. Section 43 of the setting tool contains a longitudinal bore 44 and diametrically opposed holes just above the reduced lower end to receive pins 49. Section 43 is also formed with holes 53 as shown in Fig. 2 for purpose later explained.

Above section 43 and resting thereon is a head 45 which is formed with a reduced shaft section 46 which extends downward into bore 44. Shaft portion 46 has on its lower end and on opposite sides a pair of flat faces 47. Transversely through shaft 46 and between faces 47 is a recess 48. Mounted slidably in recess 48 and extending laterally therefrom through holes in the lower part of cylinder 43, through holes 11 in body 2, and holes 39 in sleeve 36, are pins 49 of a square cross-section, whose thickness is cut away for slightly more than half their length as shown at 50 in Fig. 2 so as to interlock each other when drawn inwardly. Pins 49 are held in place and guided by screws 52 which ride slidably in slots 51 cut in faces 47. Slots 51 extend diagonally from top to bottom of faces 47 but in opposite directions on the respective faces 47. Holes 53 in cylindrical section 43 are for the purpose of accommodating tools for inserting screws 52 into pins 49.

At the upper end of the shaft section 46 is a shear pin 57 extending through the upper end of section 43 and preventing relative movement between these two main component parts of the setting tool. On the top of the head 45 is an externally threaded stud 54 which screws into the coupling 55. Coupling 55 anchors the cable 56 which extends upwardly to the derrick.

The foregoing description has dealt with one form of the apparatus embodying the invention. The method of operating this adaption will now be described:

The setting tool is inserted in the packer body and the head 45 of the setting tool pressed downward. This causes the screws 52 to slide upward in the slots 51 and expand the pins 49 outwardly through the holes 11 and 39 in sleeves 2 and 36 respectively. In order to do this sleeve 36 must be 70 75

slipped downwardly to engage the setting pins, which at the same time compresses the spring 42 between the shoulders 34 and 37. After this is done the shear pin 57 is inserted, thus preventing movement between parts 43 and 46 of the setting tool. The coupling 55 may then be screwed on and the whole assembly lowered into the well on cable 56.

As long as the motion is downward the packer 10 moves freely, the lower slips 30 sliding upwardly and the upper slips being held out of engagement by sleeve 36 and the setting pins 49.

As soon as the desired depth is reached a pull 15 is exerted on the cable 56 and this upward movement of the packer causes the lower slips 30 to slide downward in the slots 29 of the setting blocks 25 and to dig wickers 31 into the wall of casing 1.

Further upward pull on the cable causes blocks 20 25 to slide downward in slots 4 and to exert pressure on the top of the ring 23. The inclined surface 24 pressing downwardly against the surface 22 of packer ring 20 causes the surface 8 of adapter 6 to bear against surface 21 of the ring 20 thereby expanding the packer ring 20 to form a seal against the inside of the casing 1.

Still more upward pull is exerted on the cable 56 which causes the pin 57 to shear, allowing the shaft 46 of the setting tool to slide upwards in the section 43, moving the slots 51 in an upwardly direction. This causes the pins 49 to retract within the section 43 which releases the sleeve 36 and allows the spring 42 to snap sleeve 36 upwardly, causing the upper slips 41 to travel upwardly and outwardly on inclined surface 10 of body 2, forcing the teeth on slips 41 to bite into the casing 1 and preventing any downward movement of the packer. At the same time the setting tool may be removed from the well.

When it is desired to retrieve the casing plug, a casing spear or tool on a line may be lowered into the well to catch in the groove 18 of sleeve 12 and hook under the bead 19. Then sufficient pull is applied upwardly to shear the pin 17, which allows the sleeve 12 to be pulled up until the shoulder 15 meets the shoulder 16. This stops the upward travel of the sleeve 12 and at the same time removes the support from the inside surfaces of blocks 25, allowing the spring 42 to push sleeve 33 downward. The bevelled inside lower end of sleeve 33 pushes downward on the inclined surfaces 28 of blocks 25 causing the blocks to fall together inwardly, thereby withdrawing the teeth 31 of slips 30 from contact with the casing wall. The removal of the lower slips allows the sleeve 33 to drop to the top of the ring 23 thereby decompressing the spring 42 and releasing the upper slips 40. The whole packer may then be withdrawn from the well on the casing spear.

Referring now in detail to Figs. 4, 5, and 6 of the drawings which illustrate another modification of an apparatus embodying the present invention, numeral 1 designates the casing of an oil well in which is hung by a cable 56, a cable anchor and coupling 55 to which is attached a setting tool 99.

The packer comprises a cylindrical body 58 having approximately two-thirds of its lower external surface 59 of a reduced diameter and having for approximately the lower one-half of its internal surface an enlarged bore 60. At the extreme lower end of body 58 are a plurality of longitudinal slots 61 and an internal screw thread 62.

Screwed on the screw threaded portion 62 of the packer body 58 is a packer adapter 63 formed with an internal screw threaded portion in which a bull plug 7 is fastened. The adapter 63 has a downwardly and outwardly inclined surface 64.

The body 58 is formed at the upper end thereof with an upwardly and outwardly extending external conical surface 103. At the top of the reduced section 59 is a shoulder 65. Directly beneath the shoulder 65, the body 58 is provided with a longitudinal slot 66. Slidably mounted within the packer body 58 is a recovery nipple or sleeve 67, the upper portion thereof having a surface 68 of a diameter to slide freely inside the upper bore of body 58. The lower portion 69 of the sleeve 67 slides on the inner surface of bore 60. The enlarged bore 60 of body 58 forms a shoulder 71 which acts as a stop for shoulder 70 of recovery nipple 67 when said nipple is moved upwardly.

Relative movement between the body 58 and the sleeve 67 is prevented by a shear pin 72, said pin serving to retain the sleeve 67 in contact with the upper edge of the adaptor 63. The sleeve 67 is formed adjacent its upper end with an internal annular groove 73, forming an annular hooked bead for the purpose hereinafter explained.

Surrounding the packer adaptor 63 is an oil resistant or neoprene packer sleeve 75, its lower end shaped with an internal conical face 76 to fit face 64 of adapter 63, and its upper end shaped with an internal conical face 77 to fit an external conical face 78 which is on the lower end of a circumferential ring 79 which surrounds the lower end of body 58.

Ring 79 normally covers the lower end of body 58, the lower ends of slots 61, and the lower ends of setting blocks 80 which are mounted for vertical sliding movement in each of the slots 61.

Each setting block 80 has an internal part-cylindrical surface contacting the outer surface of portion 69 of sleeve 67. Each setting block furthermore has an external, downwardly and outwardly inclined surface provided with a longitudinal dove-tailed slot 86, an upwardly and inwardly extending external surface 84, a part-cylindrical upper end 82 and a semi-circular lip 83. Lower slips 87 are formed with upwardly pointed teeth or wickers 88 and are provided with dove-tailed tongues 89 which ride slidably in grooves 86 of blocks 80.

The upper ends 82 of blocks 80 are covered by a circumferential ring 85, whose internal surface slidably engages the external surface of portion 59 of body 58. Ring 85 is formed with an annular internal groove to fit the lips 83 of blocks 80, and furthermore with an internal inclined surface to fit the surface 84 of blocks 80.

Encircling the reduced portion 59 of body 58 is an annular sleeve 90, the inner surface of the upper end of which slides on the upper portion of body 58 and which has an inwardly directed shoulder 91. Furthermore sleeve 90 is provided with an opening 102 for access to a shear pin 101.

Attached to the upper end of sleeve 90 are a plurality of spring arms 95 extending upwardly and terminating in upper slips 96 which are provided with downwardly extending teeth or wickers 97, and downwardly and inwardly inclined surfaces 98 intended to contact inclined surfaces 103 of body 58.

Sleeve 90 is also provided with an opening to 75

receive a bushing 92, said bushing being formed to press in ring 90 and to fit slidably in the slot 66. Positioned in bushing 92 is a shear pin 93.

Inserted in the body 58 and extending downwardly to near the top of recovery sleeve 67, is a reduced shaft portion 100 of a setting tool 99, into which the shear pins 93 and 101 extend. Shear pin 93 in bushing 92 prevents relative movement between bushing 92 and therefore ring 90, and shaft 100 of the setting tool. Shear pin 101 prevents relative movement between the shaft 100 of the setting tool and the packer body 58.

The method of operating this form of the invention will now be described:

The retrievable plug and packer are lowered in the well on the cable 56. Downward movement of the packer will not be retarded as the lower slips 87 will slide up on setting blocks 80. When the direction is changed however, the lower slips engage the walls of casing 1 by sliding downwardly and outwardly on the blocks 80.

Increased pull upwardly will cause blocks 80 to exert pressure on the top edge of ring 79 while moving downwardly in slots 61. This causes tapered face 78 of ring 79 to bear on face 77 of the neoprene ring 75, at the same time wedging face 76 of said ring 75 against face 64 of packer adaptor 63, thereby forcing the ring 75 outwardly against the casing 1. The packer and lower slips are now set in place.

Further upward pull on the setting tool 99 causes the light shear pin 101 to shear and lets the ring 90 be pulled upwardly by the setting tool 99 and the pin 93, sliding the upper slips on the conical surface 103 of body 58 upwardly against the casing 1. A slight additional pull upward digs the wickers 97 into the casing and prevents any downward movement of the packer, and at the same time brings the shoulder 91 and the upper edge of bushing 92 against the shoulder 94. A final pull upward on the cable 56 shears the large shear pin 93 and allows the setting tool to be pulled up and out of the well, leaving the plug tightly in place in the well.

To retrieve the packer, a conventional casing spear, or tool on a line, is lowered in the well to catch in the annular groove 73 and under the bead 74 of sleeve 67. The sleeve 67 is pulled upwardly, breaking the pin 72 and setting the shoulder 70 against the shoulder 71 of the body 58. This action removes the support from the inside of the setting blocks 80, allowing them to disengage from ring 85 and fall inwardly, releasing the pressure on the ring 79 and also on the packer ring 75. A slight pull upwardly disengages the upper slips 96 from the casing and allows the plug to be drawn from the well.

It will thus be seen that there is provided two devices in which the several objects of the present invention are achieved and which are well adapted to meet the conditions of practical use.

In the foregoing description, element 7 has been designated as a bull plug. It will be understood that any other device which is desired to be suspended in the casing, such as a choke valve, back pressure valve, casing liner, and so forth, may be substituted for the bull plug. The use of two of the devices shown in tandem with a bull plug or check valve on the bottom of the lower one and with tubing connected to the top of the upper one for use in squeeze-cementing is also contemplated. Other uses for this versatile well packer will occur to those skilled in the art.

As various other embodiments might be made

of the above described invention, and as various changes might be made in the embodiment herein set forth without departing from the spirit of the invention, it is to be understood that all matter herein set forth or shown in the accompanying drawings is to be interpreted as illustrative and not in a limiting sense.

Having thus described my invention, I claim as new and desire to secure by Letters Patent:

1. A retrievable device adapted to be set in an oil well casing, comprising a body formed with a plurality of longitudinal slots, setting blocks slidably mounted within said slots and carrying gripping members adapted to engage the inner surface of an oil well casing, a sleeve within said body having limited sliding movement relative thereto, and contacting the inner surface of said blocks, and adapted to be moved to a position for clearing said blocks, and a shear pin connecting said sleeve to said body, to hold said sleeve in a position for contacting the inner surfaces of said setting blocks.

2. A retrievable device adapted to be set in an oil well casing comprising a body formed with a plurality of longitudinal slots, setting blocks slidably mounted within said slots and carrying gripping members adapted to engage the inner surface of an oil well casing, a sleeve within said body having limited sliding movement relative thereto, and contacting the inner surface of said blocks, and adapted to be moved to a position for clearing said blocks, a shear pin connecting said sleeve to said body, to hold said sleeve in a position for contacting the inner surfaces of said setting blocks, said body having an external conical surface spaced longitudinally from said slots, slip wickers adapted to ride on said conical surface, and means for forcing said slip wickers into engagement with the casing.

3. A retrievable device adapted to be set in an oil well casing comprising a cylindrical body, means on said body to permit said body to be moved downwardly in an oil well casing, and adapted to grip the inner surface of the oil well casing when the said body is moved upwardly, a member having limited sliding movement relative to the body, and adapted to hold said gripping means in position for gripping the oil well casing upon moving said body upwardly, a shear pin connecting the said member and said body, said member being adapted to move relative to the body, upon the pin being sheared, to a position for releasing the gripping means, so that the gripping means will not grip the oil well casing when the said body is moved upwardly.

4. A retrievable device adapted to be located in an oil well casing comprising a cylindrical body, means for suspending said body in a casing, means on said body to permit the said body to be moved downwardly in said casing, and adapted to grip the inner surface of the casing when the body is moved upwardly, a member normally having a limited sliding movement relative to the body, and adapted to hold said gripping means in a position for gripping the said casing upon moving the said body upwardly, a shear pin interconnecting the said member and said body for preventing relative movement thereof, said body having an external conical surface, a ring member slidably mounted on said body, spring means

normally tending to move said ring member in one direction relative to said body, a second set of gripping members attached to said ring member and contacting the conical surface of said body, a setting tool positioned within said body, setting pins extending from said setting tool, said ring member and said body having registering openings adapted to receive said setting pins, said pins normally restraining said spring means, means in said setting tool operable by an upward pull on said suspending means for withdrawing said setting pins from said ring member and said body, whereby said spring means can move said ring member in relation to said body and therefore bring said latter gripping members into gripping position against said casing so that said packer body will not move downwardly in the said casing.

5. A retrievable device adapted to be located in an oil well casing comprising a cylindrical body, a setting tool within said body, suspending means on said cylindrical body to allow said body to be lowered in said casing, and adapted to grip said casing upon upward movement thereof, a packer ring on said body, means on said body to expand said packer ring outwardly against said casing upon an upward pull being exerted on said suspending means, an additional set of gripping members adapted to grip said casing and prevent downward movement of said cylindrical body when said gripping members are in their operative position, and adapted to release automatically from said casing upon upward movement of said cylindrical body, a longitudinal slot in said body, a shear pin positioned slidably in said slot and connecting said second gripping means to said setting tool, a second shear pin connecting said cylindrical body and said setting tool, so that said second shear pin will hold said setting tool in a position for holding said second gripping members in their inoperative position, said suspending means being connected to said setting tool, said second shear pin being adapted to break before said first shear pin upon an upward pull of said suspending means, said setting tool adapted to move said second gripping means to their operative position upon breaking of said second shear pin, said first shear pin being adapted to break upon said second gripping members being moved to their operative position and causing said setting tool to be released from said cylindrical body, so that said setting tool may be withdrawn from said casing, a recovery sleeve within said cylindrical body, and having limited sliding movement relative thereto, a third shear pin connecting said sleeve to said body and holding said sleeve in a position for holding said first gripping means in their operative position, said sleeve being adapted to move to a position for releasing said first gripping means from said casing upon the breaking of said third shear pin, an internal annular groove on said recovery sleeve adapted to be caught by a conventional fishing tool lowered in said casing, so that said third shear pin may be broken by an upward pull on the fishing tool and said first gripping means released from said casing, whereby said cylindrical body can be retrieved from the said casing.

BOWEN MONROE DAVIS.
